UNITED STATES PATENT OFFICE.

WILLIAM D. M. SIMMONS, OF BROOKLYN, NEW YORK, ASSIGNOR TO UNDERWOOD
ELLIOTT FISHER COMPANY, OF NEW YORK, N. Y., A CORPORATION OF DELAWARE.

COPYHOLDER.

Application filed May 5, 1925. Serial No. 28,043.

This invention relates to copy-holders for use with typewriters, etc.

In typewriting speed contests a need has arisen for a special copy-holder. According to the present improvements, the copy is at about right angles to the line of vision of the typist, and no training is required in its use. It is inexpensive, and before being set up it is flat, so that several copy-holders can be packed compactly for shipment. Its surfaces are suitable for printing advertisements. It is simply and strongly made from a single blank of inexpensive cardboard.

The improved copy-holder may have a low front wall, a higher back wall, and two symmetrical side walls, and means integrally joined with certain of the walls for fastening them together detachably. Simple ledges on the front wall prevent sheets of copy from sliding.

Other features and advantages will hereinafter appear.

In the accompanying drawings.

Figure 1 is a diagram of the blank from which the copy-holder is constructed.

Figure 2 is a rear perspective view of the copy-holder in set-up form.

Figure 3 is a front perspective view of the copy-holder in set-up form with a portion of the top broken away to show an arrangement for fastening a side wall and the back end wall together.

Figure 4 is a fragmentary perspective view of the copy-holder, illustrating the fastening of a side wall to an extension of the front end wall.

The top 1 of the copy-holder may be downwardly inclined toward the front at an angle that allows the copy to lie approximately at right angles to the line of vision of the typist. The top 1 may be supported by the low, front end wall 2, the back wall 3, which is higher than the front wall, and the two side walls 4 having triangular form. Said walls 2, 3 and 4 may be hinged to the top 1 along crease or fold lines 15, 16 and 17. Line 15 need not be continuous.

In setting up the copy-holder, the side walls 4 may be folded to their approximate operative positions along the lines 17, and the flaps 5, which are provided on the back ends of the side walls, may be folded inwardly along the lines 19, so as to lie against the inside surface of the end wall 3 when the latter is folded along line 16. The end wall

3 may be locked to the flaps 5 by its tongues 10 engaging in slits 12 in flaps 5, Figure 3.

The low wall 2 may next be folded along interrupted fold-line 15, taking care not to fold the bracket-portions 8. An extension 6 of the end wall 2 may be folded inwardly about the line 18, to lie against the bottom edges 23 of side walls 4. The front end extension 6 may be provided with flaps 7 arranged to fold inwardly about lines 22, so as to lie against and on the outside of the side walls 4, and enter the slits 13 in the side walls 4 and be locked to the walls by bending the tips 20 transversely to the side walls 4 along the fold-lines 21, as illustrated in Figure 4. The tips 20 may be provided by cutting the slits 14 a short distance into the flaps 7.

The low wall 2 is provided with the two bracket-portions 8 cut out of the top 1, by making the slits 9 in three sections joined at obtuse angles and having the slits start and stop on the line 15, which line will not be marked or scored across the bottom of the bracket-portions 8.

When the end wall 2 is folded to its normal position at approximately right angles to the top 1, the bracket-portions 8 will project above the plane of the top 1.

When the copy-holder is set up for use, the brackets 8 keep the copy from sliding.

To allow the copy-holder to be readily lifted with one hand, bottom portions of the side walls 4 are formed with finger-holes at 24.

The copy-holder can be quickly unfolded or "knocked down" to the flat form shown in Figure 1. It can also be readily seen that the copy-holder can be folded into various convenient forms for packing away.

Practically all of the outside areas of the end and side walls of the copy-holder may be used for printing advertisements thereon, thus making it adaptable for use as an advertising novelty, especially for "business shows".

Variations may be resorted to within the scope of the invention, and portions of the improvements may be used without others.

Having thus described my invention, I claim:

1. A collapsible copy-holder for typists, comprising a foldable cardboard box provided with a top downwardly inclined toward the front of said copy-holder; two

- rectangular end walls and two side supporting walls for said top; the two side walls having extensions foldable to fit on the interior of the back rectangular wall with locking means between said interior extensions and the exterior back wall, the front end wall having an extension foldable under the two side walls, and locking means extending upwardly and through the side walls
- 5 locking means between said interior extensions and the exterior back wall, the front end wall having an extension foldable under the two side walls, and locking means extending upwardly and through the side walls
- 10 two brackets arranged at right angles to said top and adjacent its lower end; and means for allowing said brackets to lie in the same plane with said top when said copy-holder is knocked down flat.
- 15 2. A collapsible copy-holder for typists, comprising a foldable cardboard box provided with a top downwardly inclined toward the front of said box; front and rear rectangular end walls and two symmetrical side walls arranged for upholding said top the front end wall having an extension foldable under the side walls; and detachably engageable means for fastening said walls together, said side walls having portions adjacent their lower edges cut away so that a typist's fingers may be inserted under said side walls to lift said box.
- 20
- 25
3. A collapsible copy-holder for typists, comprising a foldable cardboard box made from a single blank provided with a top downwardly inclined toward the front of said box; a front end wall and a back end wall higher than said front end wall; and
- 30
- two symmetrical side walls, said end and side walls integrally hinged to said top, said side walls each provided with a slit adjacent said front end wall and an integrally-hinged flap, said flap having a slit therein arranged for detachable engagement with a tongue integrally joined to said back end wall for fastening said back end wall and said side walls together, said front end wall provided with an integrally-hinged extension having two flaps, each of said flaps of said extension provided with a locking tongue, said flaps of said end extension arranged for detachable engagement in said slits in said side walls adjacent said front end wall, and said locking tongues arranged for locking said extension-flaps in said slits in said side walls, and said front end wall arranged with two integrally-joined brackets projecting above said inclined top.
4. A collapsible copy-holder for typists comprising a foldable box made from a single blank provided with a top downwardly inclined toward the front of said copy-holder, a front end wall, a rectangular back end wall and two sides supporting said top and integrally hinged thereto, said front end wall having a portion extending back under the side walls, and detachable engageable means integral with said blank arranged for fastening said walls together.

WILLIAM D. M. SIMMONS.
